ABSTRACT

A breech mechanism for firearms includes a chamber insert adapted to be secured in the chamber of a rifle or the like for easily converting the rifle to fire either caseless cartridges or standard case-type cartridges depending upon the insert used. A modified bolt is provided for use with the chamber insert.

**BREECH MECHANISM WITH INTERCHANGEABLE
CHAMBER INSERTS FOR CASELESS AND CASE-TYPE
CARTRIDGES**

BACKGROUND OF THE INVENTION

The present invention relates to means for converting a rifle to fire either caseless cartridges or standard case-type cartridges.

A chamber insert is provided for threading into the chamber of a rifle or the like and in one form includes a generally cylindrical flexible side wall portion for use with caseless cartridges and includes means for holding the caseless cartridge in the breech of a rifle or the like in a gas-tight manner. A special bolt is provided for use with the chamber insert and includes an elongate cylindrical portion adapted to be disposed in surrounding relationship to the cylindrical flexible side wall of the chamber insert.

In another form of the invention, a chamber insert is provided for threading into the chamber of the rifle for use with standard case-type cartridges and includes a standard bolt for use with the standard chamber insert.

The bolts and chamber inserts are readily interchangeable in conventional rifles for converting the rifle from use with standard case-type cartridges to use with caseless cartridges.

OBJECTS OF THE INVENTION

It is an object of the invention to provide a breech mechanism for firearms for readily converting the firearms from use with standard case-type cartridges to use with caseless cartridges and vice versa.

It is another object of this invention to provide a chamber insert and bolt specially constructed to be readily inserted and removed from the breech of the rifle or the like for converting a rifle from use with standard case-type cartridges for use with caseless cartridges.

BRIEF DESCRIPTION OF THE DRAWINGS

FIG. 1 is a sectional view in elevation of a rifle incorporating the chamber insert and bolt for firing caseless cartridges.

FIG. 2 is a sectional view in elevation of a rifle incorporating the chamber insert and bolt for use with case-type cartridges;

FIG. 3 is an exploded view partly in section showing the manner in which a spanner wrench is used for inserting and removing the chamber insert from a rifle for firing caseless cartridges;

FIG. 4 is a sectional view in elevation illustrating the breech and barrel of a rifle with the chamber insert and bolt removed;

FIG. 5 is a sectional view in elevation of the chamber insert for use with caseless cartridges;

FIG. 6 is a sectional view in elevation of the special bolt used with the chamber insert for firing caseless cartridges;

FIG. 7 is a sectional view in elevation of the chamber insert for use with standard case-type cartridges; and

FIG. 8 is a sectional view in elevation of the bolt for use with the chamber insert for firing case-type cartridges.

DETAILED DESCRIPTION OF THE INVENTION

Referring now to the drawings, wherein like reference numerals refer to like parts throughout the several views, the form of the invention for use with caseless cartridges is depicted in FIGS. 1, 5 and 6. The barrel of a rifle or the like is indicated generally at 1 and includes a reduced end portion 2 threaded externally at 3 and on which is threaded a Mauser type breech 4 threaded internally at 5 for mating cooperation with the external threads 3 on the reduced end portion 2 of barrel 1. The breech 4 includes a bore 6 therethrough for receiving a Mauser type bolt 7 and has locking lug recesses 6' therein for receiving the locking lugs 8 of the bolt 7, which is shown at battery position in FIG. 1. A bore 9 is formed lengthwise through the barrel and is enlarged at one end at 10 and has internal threads 11 thereon, the bore 10 being joined with the bore 9 by a frusto-conical reference cone or surface

12. The chamber insert is depicted generally at 13 and has a bore 14 therethrough substantially commensurate in diameter with the rifle bore 9. The bore 14 includes an arcuately shaped enlarged bore portion 15 extending from one end of the insert to adjacent the other end thereof and defines a relatively thin, tapered cylindrical side wall 16 made, for example, of flexible spring steel or the like. One end of the chamber insert is externally threaded at 17 for mating cooperation with the internal threads 11 in the bore of the rifle barrel. A frusto-conical shoulder 18 is formed on said one end of the chamber insert and abuts the reference cone or surface 12 in the barrel in a gas-tight manner when the chamber insert is properly seated in the chamber. A caseless cartridge C is fitted within the chamber insert and includes a propellant 19 substantially filling the arcuately tapered cylindrical cavity within the chamber insert. A projectile 20 is received within the reduced bore portion 14 of the chamber insert and extends into bore 9 of the barrel 1. The Mauser type bolt 7 includes an elongate cylindrical relatively thin-walled projection or sleeve 21 disposed in close surrounding relationship to the side wall 16 of the chamber insert. An ignition bore or opening 22 is formed longitudinally through the bolt 7 establishing communication between the chamber containing the propellant 19 and an ignition source which may comprise a primer or an electrical ignition or the like.

The chamber insert 13 described above is inserted and removed from the breech by means of a spanner wrench indicated generally at W in FIG. 3 and which includes an elongate cylindrical shank portion 49 having longitudinally projecting lugs 50 at one end thereof for cooperative engagement in recesses R formed adjacent the threaded portion of the chamber insert 13. A handle 51 is fitted laterally in the other end in the spanner wrench for turning the wrench to thread the chamber insert into and out of the recess within the barrel.

Referring now to FIG. 2, that form of the invention for use with standard case-type cartridges is depicted. A rifle barrel 23 has a longitudinal bore 24 extending therethrough enlarged at one end at 25 and internally threaded in the enlarged bore portion at 26. A frusto-conical reference cone or surface 27 joins the threaded bore portion 26 with the bore portion 24. The end of the barrel is externally threaded at 28 and a breech 29 internally threaded at 30 is threadably received thereover. A longitudinal bore 31 extends through the breech and includes locking lug recesses 32 at one end for receiving the locking lugs 33 of a bolt 34 received in the bore 31 of the breech. A standard chamber insert 35 is secured within the enlarged bore portion 25 of the barrel by means of external threads 36 thereon in cooperative engagement with the threads 26 in the barrel. The forward end of the chamber insert has a frusto-conical shoulder or surface 37 thereon in tight abutting contact with reference surface 27, which forms a gas-tight fit when the chamber insert is properly seated. A longitudinal bore is formed through the chamber insert and includes a first portion 38 at one end substantially commensurate in diameter with the diameter of rifle bore 24 and a second portion 39 enlarged relative to portion 38, the two portions being joined by a tapered shoulder 40.

A standard case-type cartridge indicated generally at C is received within the chamber insert and includes a generally cylindrical side wall 41 of brass or the like with a rim 42 at one end thereof disposed over the end of the side wall of the chamber insert in abutting relationship thereto. A percussion cap or primer 43 is fitted centrally within the base of the cartridge for igniting a propellant 44 substantially filling the case to fire a projectile 45 through the bore of the rifle.

The bolt 34 fitted within the bore 31 in breech 29 is shown at battery and has a longitudinal bore 46 through the center thereof in which is slidably received a firing pin 47 for striking the percussion cap or primer 43 to fire the projectile 45 from the barrel of the rifle. The end of the bolt includes a shallow recess 48 for receiving the raised portion of the base of cartridge C.

FIGS. 4 through 8 illustrate the interchangeability of the caseless-cartridge chamber insert and bolt with the standard case-type chamber insert and bolt. In FIG. 4, a typical rifle barrel and breech mechanism, such as described in FIG. 2, is shown assembled together, the barrel 23 including a bore 24 therethrough enlarged at one end at 25 and internally threaded at 26 for matingly receiving the threads of one of the insert chambers therein. A reference cone or surface 27 is formed between the threaded end of the enlarged bore 25 and bore 24 against which one end of the chamber insert is adapted to be seated in a gas-tight manner.

FIG. 5 and 6 illustrate the chamber insert and bolt, respectively, for use with caseless cartridges and in order to adapt the rifle mechanism illustrated in FIG. 4 to use with caseless cartridges, the chamber insert 13 is threaded into the enlarged bore portion 25 by use of the spanner wrench W, with the threads 17 on the end of the insert chamber in mating engagement with threads 26 within the bore of barrel 23. The chamber insert is threaded into the bore until the reference cone or frusto-conical end of the insert comes into tight fitting abutting contact with the reference cone or surface 27 within the bore of the rifle. The bolt 7 is then fitted into place by sliding the bolt longitudinally in the bore 31 with the cylindrical sleeve 21 fitting in tight surrounding relationship with side wall 16 of the chamber insert and with the locking lugs 8 received in the locking lug recesses 32 in the breech mechanism 29 when the bolt is at battery.

Alternatively, the rifle mechanism may be converted for use with standard case-type cartridges by removing the bolt and chamber insert described above and threading the chamber insert 35 into place with the threads 36 on one end thereof in mating engagement with threads 26 until the reference cone or end 37 of the chamber insert come into tight fitting abutting contact with the reference cone or surface 27 within the bore of the rifle. The standard bolt 34 is then fitted into position with locking lugs 33 received in the locking lug recesses 32 in the breech mechanism.

Both forms of the invention provide a secure gas-tight fit within the breech of the rifle thus insuring reliable and effective firing of a cartridge received therein. For example, the reference surfaces 12 and 18 and 27 and 37 are fitted in gas-tight engagement and the cylindrical side walls of the chamber inserts are slightly flexible and accordingly flex outwardly into close fitting gas-tight engagement with the sleeve 21 or the wall of bore 25 as the case may be when the cartridge is fired.

The components of both forms of the invention described hereinbefore are readily manufactured with production equipment. For example, the clearance between the exterior of the sleeve 21 and the bore of the barrel should be maintained from about 0.001 inches to 0.002 inches which is easily achieved with production equipment.

As this invention may be embodied in several forms without departing from the spirit or essential characteristics thereof, the present embodiment is therefore illustrative and not restrictive, and since the scope of the invention is defined by the appended claims, all changes that fall within the metes and bounds of the claims or that form their functional as well as conjointly cooperative equivalents are therefore intended to be embraced by those claims.

I claim:

1. A breech mechanism for firearms for selectively converting a firearm to fire a caseless cartridge and case-type cartridge, comprising a first elongate chamber insert and a second elongate chamber insert, said first and second inserts being independently used one at a time in a firearm, and each

- insert having an externally threaded forward end portion for cooperative threaded engagement with internal threads in a rearward end portion of the barrel of said firearm, said forward end portion of each said insert being externally conically tapered to effect a gas-tight seal with a mating, conically tapered reference surface in said barrel, a longitudinal bore extending through each said insert and having a diameter at the forward end thereof substantially the same as the diameter of the bore of the barrel of said firearm, the remainder of said bore in each insert being diametrically enlarged and extending over a major portion of the length of each said insert to define a cartridge receiving chamber having a relatively thin, flexible, rearwardly extending cylindrical side wall so that upon explosion of a cartridge received in said cartridge receiving chamber, said cylindrical side wall flexes outwardly to effect a gas-tight seal with said firearm, and first bolt means and second bolt means for cooperation with a respective chamber insert and with said firearm for firing a cartridge received in said firearm, said inserts and said bolt means being readily interchangeable in said firearm to quickly and easily convert said firearm from use with case-type cartridges to use with caseless cartridges and vice versa.
2. A breech mechanism as in claim 1, wherein: said enlarged bore portion in said first insert is arcuately tapered with an increasing diameter from the forward end thereof to the other end thereof so that said cylindrical side wall has a gradually decreasing thickness toward the rearward end thereof; and said first bolt means includes a longitudinally extending sleeve for close fitting disposition around said cylindrical side wall, said first insert and said first bolt means constructed to fire a caseless cartridge.
3. A breech mechanism as in claim 2, wherein: a longitudinal ignition bore is formed through said first bolt for firing said caseless cartridge.
4. A breech mechanism as in claim 1, wherein: said enlarged bore portion in said second insert is cylindrical and has an end surface at the rearward end thereof against which the rim of a case-type cartridge is adapted to be seated; said bolt including a recess in the forward end thereof for receiving a raised portion at the base of said case-type cartridge when said second bolt and said second insert are assembled in a firearm with a case-type cartridge fitted in said second insert.
5. A breech mechanism as in claim 4, wherein: a longitudinal bore is formed through said second bolt and a firing pin is slidably fitted within said bore for firing a cartridge in said second insert.
6. A breech mechanism as in claim 1, wherein each said chamber insert is constructed of flexible spring steel.
7. A breech mechanism for firearms for selectively converting a firearm to fire a caseless cartridge and a case-type cartridge, comprising a first elongate chamber insert and a second elongate chamber insert, said first and second inserts being independently used one at a time in a firearm, and each insert having releasable securing means thereon for cooperative engagement with complementary securing means in said firearm, each of said inserts having a rearwardly extending cylindrical side wall defining a cartridge receiving chamber therein and constructed so that upon explosion of a cartridge received in said cartridge receiving chamber, said insert effects a gas-tight seal with said firearm, and bolts means for cooperation with said chamber inserts and with said firearm for firing a cartridge received in said firearm, said inserts being readily interchangeable in said firearm to quickly and easily convert said firearm from use with case-type cartridges to use with caseless cartridges and vice versa.
